(57) CLAIM

The ornamental design for a magnetic tape transcriber, as shown and described.

DESCRIPTION

FIG. 1 is a perspective view of a magnetic tape transcriber showing our new design.

FIG. 2 is another perspective view thereof.

FIG. 3 is a front elevational view thereof.

FIG. 4 is a rear elevational view thereof.

FIG. 5 is a left side view thereof.

FIG. 6 is a right side view thereof.

FIG. 7 is a top plan view thereof; and,

FIG. 8 is a bottom plan view thereof.

The broken lines in the drawings of FIGS. 1-8 are included to show portions of the magnetic tape transcriber that form no part of the claimed design.
